UNITED STATES PATENT OFFICE.

WALTER STEWART BORLAND, OF SASKATOON, SASKATCHEWAN, CANADA.

WINDOW ATTACHMENT.

1,373,709.

Specification of Letters Patent.

Patented Apr. 5, 1921.

Application filed December 23, 1919. Serial No. 346,864.

To all whom it may concern:

Be it known that I, WALTER STEWART BORLAND, of the city of Saskatoon, in the Province of Saskatchewan, Canada, have invented certain new and useful Improvements in Window Attachments, of which the following is the specification.

The invention relates to improvements in window attachments and particularly to an extension window structure and an object of the invention is to provide an extension window structure applied to a window frame and which will allow of clear uninterrupted vision both forwardly, rearwardly and laterally from the interior.

A further object of the invention is to construct the attachment so that it can be readily connected to existing window frames and removed therefrom when desired and further to arrange the attachment so that it can be collapsed when not in use.

A still further object is to provide an extension window frame particularly adapted for use on the cabs of locomotive windows whereby, when the attachment is installed, the engineer can see clearly both ahead and to the rear and without necessitating putting his head out into the open air as at present occurs.

With the above more important and other minor objects in view, which will become more apparent as the description proceeds, the invention consists essentially in the arrangement and construction of parts hereinafter more particularly described and later pointed out in the appended claims, reference being had to the accompanying drawings, in which:

Figure 1 is a side view showing my window attachment as applied on the cab of a locomotive engine.

Fig. 2 is a rear view.

Fig. 3 is an enlarged detailed side view of the window attachment.

Fig. 4 is an end view thereof.

Fig. 5 is an interior view.

Fig. 6 is a top plan view.

Fig. 7 is a vertical cross sectional view through the attachment at 7-7', Fig. 5.

Fig. 8 is a vertical longitudinal sectional view through the attachment at 8-8', Fig. 6.

Fig. 9 is a horizontal sectional view at 9-9', Fig. 3.

Fig. 10 is a view similar to Fig. 9 with the side windows opened.

Fig. 11 is a view of the attachment in the folded position.

Fig. 12 is an enlarged detailed front view of the jack screw. 60

Fig. 13 is a vertical sectional view through the plate and bearings carrying the jack screw, the jack screw being shown in side elevation.

Fig. 14 is a perspective view of the socket for the jack screws. 65

Fig. 15 is a perspective view showing a modified form of the attachment.

In the drawings like characters of reference indicate corresponding parts in the several figures. 70

In the present disclosure I have shown the extension frame as attached to the cab of a locomotive engine but I wish it to be distinctly understood that I do not wish to be limited to this particular use of it as there are many other places where the said extension frame could be used to advantage. This feature will be readily appreciated and is not further enlarged upon. 75

Referring now to the drawings:

1 represents the cab of a locomotive engine having a window opening 2 therein, the opening being bounded by the window frame 3, this being actually formed as part of the cab side. 80

Customarily the opening is closed by a sliding window sash 4 which slides ahead within the guides 5 and 6 to a position in advance of the opening as best shown in Fig. 1.

To the side of the cab I attach my box like extension window 7, such extension window inclosing the opening 2 and providing head room for the engineer. The extension window is formed from a plurality of hinged sections arranged and constructed as now described. 95

The ends 8 and 9 of the extension frame are preferably formed from angle iron bent and cut to form open centered substantially rectangular end frames. To the bottom of the end 8 I connect pivotally as by hinges 10 an upwardly swinging base or bottom section 11, the free end of which is designed to seat on the top side of the angle iron forming the bottom of the other end 9 of the extension frame. To the top of the end piece 9 I secure as by hinges 12 a top section 13, the free end of which overlies the upper end of the end piece 8. The sections 11 and 13 are preferably flat metallic plates 100

105

110

and they are fitted at their outer edges with inturned stop flanges 14 and 15. The top section 13 is pivotally fastened by hinges 16 to the end member 8.

5 In order to give rigidity to the structure it is fastened to the existing window frame which, in the present instance, is the window frame of the cab. A releasable fastening is provided, which fastening comprises 10 in the present instance four similar jack screws 17, 18, 19 and 20, the jack screws being carried in each instance by bearings 21 and 22 provided on a carrying plate 23 which is secured to the adjacent end 15 pieces. The inner ends of the jack screws are fitted with pivoted levers 24 which can be swung up and down and which provide an easy means for operating the screws.

When the extension frame is to be attached 20 the jack screws are drawn in and the extension frame is fitted against the outer face of the window frame, the withdrawn jack screws at this time being contained within the frame as best shown in Fig. 2. 25 Obviously by tightening up the jack screws against the top and bottom of the window frame the extension frame will be positively clamped in position, the two end members 8 and 9 then becoming stationary elements 30 which hold the other parts of the structure in position. To prevent undesirable wearing of the window frame I have provided metallic sockets A to receive the ends of the jack screws.

35 Here it will be observed that the inner side of the extension frame opens through the interior of the window frame to the interior of the cab and that there is sufficient width in the extension frame to allow the 40 engineer to extend his head into the extension frame through the window opening 2.

In the outer corners of the extension frame I locate stationary vertically disposed corner posts 25 and 26 and to the corner posts 45 I secure end window sashes 27 and 28 which are hinged to the posts at 29 so that they can be opened when desired for cleaning and other purposes. These end sashes close the openings in the end frames 8 and 9. 50 To the corner posts I hinge also at 30 further window sashes 31 and 32 and these sashes carry other hinged sashes 33 and 34, the arrangement being such that when the sashes are opened or extended they fully 55 close the opening in the outer side of the extension frame as best shown in Fig. 9. The hinges connecting the latter sashes together and to the posts are arranged so that the said sashes can be folded in against 60 the sashes 27 and 28 as shown in Fig. 10 and in such folded position they are entirely contained within the ends 8 and 9.

The structure so formed from the various hinged sections and sashes can be folded 65 up into a compact form once it is released

from the frame by undoing the jack screws. In folding, the sashes 31, 32, 33 and 34 are first folded into the end frames. Then the end section 8 is swung up to lie on top of the top section 13. Then the bottom section 11 70 is folded in against the end section 8 and the end section 9 is closed in against the underside of the top section. In this collapsed or stacked position the extension window appears as shown in Fig. 11. When 75 it is stacked it is very convenient to carry about, such as when it is to be changed from one cab to another.

The flanges 14 and 15 form a stop for the sashes 31, 32, 33 and 34 when they are 80 opened out as shown best in Figs. 7 and 9. In Fig. 15 I have shown a modification of this device which, while still being collapsible, is attached by hinges to the side of the cab. In this structure the top and bottom sections 35 and 36 and the end window sections 37 and 38 are hinged directly to the cab side and are arranged so that the end sections will pass between the top and bottom sections when in use. The front window section 39 is then closed in against the end sections and between the top and bottom sections and is held fast by spring clips 40.

From the above description it will be apparent that when this device is applied to a window frame one can see clearly either ahead, behind or outwardly without any difficulty and such a device lends itself particularly to use on locomotive cabs where, 100 under present conditions, an engineer has to put his head out of the cab window to see ahead and back and under weather conditions which are very adverse and particularly when traveling at a comparatively 105 high rate of speed. It will be seen also that the sash sections are all arranged so that they can be readily swung inwardly for cleaning or ventilating purposes, as occasion may demand.

110 What I claim as my invention is:—

1. The combination with a window frame, of a box like window attachment having the inner side open and the outer side and ends fitted with window sashes and jack screws 115 carried by the inner side of the extension window and engageable with the top and bottom of the window frame and detachably securing the extension window to the window frame.

2. The combination with a window frame, of a box like window attachment having the inner side open and the outer side and ends fitted with window sashes and jack screws 125 carried by the inner side of the extension window and engageable with the top and bottom of the window frame and detachably securing the extension window to the window frame and sockets provided on the window frame to receive the jack screws. 130

3. The combination with a window frame, of an extension frame demountably attached to the window frame and comprising open centered substantially rectangular end frames, a base section pivotally secured to one of the end frames and bearing on the opposing end of the other end frame, a top section pivotally secured to both of the end frames, inwardly swingable window sashes 10 mounted in the end frames and inwardly swingable window sashes pivotally secured to the end frames and adapted when opened to close the outer side of the extension frame and with all sashes designed to stack within 15 the end frames.

4. An extension window for window frames comprising an open centered frame consisting of top, bottom and end sections, said end sections being open centered, a 20 swinging sash mounted in each end section to close the central opening thereof, and supplementary side sash sections foldably secured in each of said end sections and adapted when extended therefrom to abut 25 with the said sash sections of the opposite end section to close one side of the frame.

5. A foldable extension window for window frames comprising a pair of end sections, top and side sections carried by said 30 end sections in foldable relation therewith, and a bottom section connected to one of said end sections in foldable relation therewith and adapted to engage the other end section in the set up position of the window.

35 6. A collapsible extension window for

window frames comprising end sections, a top section hinged at its opposite ends to said end sections, the hinged connection being such as to permit one of the end sections, to be folded to lie upon the upper side 40 of the top section and the other of said end sections to be folded against the lower side of the top section, a bottom section hinged to one of said end sections and side sections hinged to each end section and adapted to 45 fold therein in the collapsed condition of the window.

7. A box like extension window for window frames comprising top, bottom and end sections and a side section closing the frame 50 at one side, said end sections being connected to the top section so as to fold one against the upper side of the top section and the other against the lower side of the top section, a bottom section foldably connected 55 to one of said end sections and adapted to engage the other end section in the set up position of the window, and complementary side sections carried by each of said end sections and adapted to fold therein, said side 60 sections being adapted to be extended into abutting relation in the set up position of the box-like extension window to form a closed side thereof.

Signed at Winnipeg, this 4th day of October, 1919.

WALTER STEWART BORLAND.
